UNITED STATES PATENT OFFICE

2,511,576

OSCILLATING BLOWER

Hewitt A. Gehres, Mount Vernon, Ohio, assignor
to Cooper-Bessemer Corporation, Mount Ver-
non, Ohio, a corporation of Ohio

Application May 14, 1945, Serial No. 593,620

2 Claims. (Cl. 230—159)

1

The invention relates to oscillating blowers such as may be used for scavenging purposes in connection with internal combustion engines, one object being to provide a blower of the above type consisting of units of such construction that they may be readily assembled side by side to provide a blower of required capacity, each of such blower units being so coordinated in respect to its driving mechanism and connections to the suction and discharge passageways that a number of the units may be assembled as above described to make up a multiple unit blower without entailing awkward assembly problems or modifications of the several units.

In accordance with the present invention the operating parts of each of the oscillating blower units are located substantially within the confines of its own plane, so that the several units may be readily driven by appropriate individual crank mechanisms connected to a crank shaft running parallel to the blower assembly, and the various units may be operated in such phase relation as to substantially balance out the strains of the power impulses. The invention also includes certain structural relationships of the various parts to enable necessary interior machining operations to be performed, and promote ready assembly. Further objects and advantages of the invention will be in part obvious and in part specifically referred to in the description herein-after contained which, taken in conjunction with the accompanying drawings, discloses certain preferred forms of oscillating blowers constructed to operate in accordance with the invention; the disclosure however should be considered as merely illustrative of the principles of the invention in its broader aspects.

In the drawings:

Fig. 1 is a vertical cross-sectional view of an oscillating blower constructed to operate in accordance with the invention, the section being taken on line 1—1 of Fig. 2.

Fig. 2 is a central longitudinal section of the blower shown in Fig. 1.

Fig. 3 is a fragmentary view similar to Fig. 2 but showing a housing construction modified to accommodate a larger number of blower units.

The invention is illustrated as applied to blower units having annular supporting members 1 which are mounted for angular oscillating movement about a central stationary shaft 2. The supporting members 1 each have a plurality of vanes or blades 3 located in spaced relation about their peripheries, and projecting radially outward. A plurality of stationary partition mem-

2

bers 4 divide the spaces through which the vanes 3 sweep into a plurality of arcuate pumping chambers 5 which are double acting in that as the vanes 3 oscillate angularly, the chambers 5 on opposite sides of the vanes 3 act alternately as intake and delivery chambers.

Adjacent the partition members 4, ports 6 are provided for each of the blower units, and each of such ports affords communication both with a suction passageway 7 and a discharge passageway 8. Appropriate suction valves 9 (Fig. 2) control communication between the suction passageways 7 and the chambers 5, and appropriate discharge valves 10 control communication between the chambers 5 and the discharge passageway 8. These valves will not be described in detail since appropriate forms thereof are known to the art. It should be noted as to the right hand blower unit of Fig. 2 for example, that the vane 3 which appears in Fig. 2 sweeps past both the right hand suction passageway 7 and the central discharge passageway 8; thus as the vanes 3 of Fig. 1 move angularly to the right from the position shown in Fig. 1, the chambers 5 to the left of the vanes will act as intake chambers to draw in fresh charges of air to be compressed from passageway 7, while the chambers 5 to the right of vanes 3 as the parts appear in Fig. 1, will act as delivery chambers from which compressed air is forced through discharge valves 10 into discharge passageway 8. Thus the vanes each straddle a suction passageway and a discharge passageway, to enable the above double acting effect to be obtained.

Each of the vane supporting members is driven by appropriate oscillating mechanism connected thereto at a point peripherally spaced between adjacent vanes 3. As shown, a crank shaft 11 running parallel to the shaft 2 is connected to cranks 12 which are in turn pivoted to crank pins 13 passing through lugs 14 on the vane supporting members 1, these lugs appearing in the lower right hand sector of Fig. 1. As shown in Fig. 2, this type of construction permits each oscillating blower unit to be powered within the confines of its own plane, so to speak, so that by using shafts 2 and 11 of appropriate length, any desired number of blower units may be readily assembled side by side. Each oscillating unit of such an assembly can self-align itself longitudinally of the machine with respect to the adjacent stationary parts with which it cooperates without affecting the other units. Furthermore it is not necessary that the adjacent units be aligned with extreme accuracy

since the adjacent members do not necessarily have to operate exactly concentrically but may float, so to speak, so that each one centers itself. Also by operating the various blower units in properly staggered phase relation to each other, the power impulses can be balanced out against each other and a smoother flow of air produced than can be obtained with the large reciprocating double acting pumps in present day use for similar purposes.

The structure as a whole may be carried within an outer housing or shell 15 within which are located the suction and discharge passageways 7 and 8 which arcuately partially surround the vane supporting members 1 as shown. Preferably however the outer shell 15 encloses a separate annular frame member 16 which is machined to fit therein and detachably connected thereto by the rings 17 (Fig. 1). The ports 6 are provided in this annular frame member 16, as are also the arcuate fins 18 which fit within inwardly projecting fins 19 on the housing 15 to define the suction and discharge passageways. This construction enables access to be had, before assembly, for the machining operations necessary to form the valve seats for the suction and discharge valve mechanisms. Circular end plates 20 (Fig. 2) in turn fit detachably within the annular frame members 16 above described and are detachably secured in position by rings 21. The partition members 4 may be held in position by through bolts 22 which pass through them and the end plates 20 above described, and also through spacing partition members 23 which are interposed between the adjacent blower units.

Fig. 3 shows a form of the invention constructed to provide three juxtaposed blower units of the character above described, the outer housing 15a providing discharge passageways 8a and 8b which alternate with suction passageways 7a and 7b, the suction valves 9a and the discharge valves 10a being as above described in connection with Figs. 1 and 2, and functioning in the same manner in cooperation with the various chambers 5a of Fig. 3. The annular housing 16a of Fig. 3 is similar to that previously described in connection with Figs. 1 and 2, except that it is provided with a larger number of arcuate fins 18a, and a larger number of the spacing partition members 23a are also employed.

While the invention has been disclosed as carried out by the specific blower constructions above described, it should be understood that changes may be made therein without departing from the invention in its broader aspects, within the scope of the appended claims.

I claim:

1. An oscillating blower assembly of the class described, having a plurality of vane supporting members disposed side by side and mounted for

angular oscillating movement about a common axis, each of said vane supporting members having a series of outwardly projecting vanes spaced about its periphery, a housing encircling said vanes and having inwardly directed partitions projecting between adjacent vanes of said vane supporting members to define pumping chambers between adjacent vanes and partitions, driving members for oscillating said vane supporting members which driving members are aligned respectively therewith in planes transverse to said axis of oscillation, said housing having suction and discharge passageways serving the respective pumping chambers, which passageways are located radially outward of the aforesaid vanes, the radially outward edge portions of each of such vanes straddling a suction passageway and a discharge passageway, and suction and discharge valves interposed respectively between said vanes and said passageways.

2. An oscillating blower assembly of the class described, having a plurality of vane supporting members disposed side by side and mounted for angular oscillating movement about a common axis, each of said vane supporting members having a series of outwardly projecting vanes spaced about its periphery, a housing encircling said vanes and having inwardly directed partitions projecting between adjacent vanes of said vane supporting members to define pumping chambers between adjacent vanes and partitions, a crank shaft substantially parallel to the axis of oscillation of said vane supporting members and having cranks angularly displaced with respect to each other and connected respectively in driving relation to said vane supporting members, said housing having suction and discharge passageways serving the respective pumping chambers, which passageways are located radially outward of the aforesaid vanes, the radially outward edge portions of each of said vanes straddling a suction passageway and a discharge passageway, and suction and discharge valves interposed respectively between said vanes and said passageways.

HEWITT A. GEHRES.
